UNITED STATES PATENT OFFICE.

EDWARD P. RICE, OF EAU CLAIRE, WISCONSIN.

JAR CLOSURE.

Application filed August 5, 1926. Serial No. 127,414.

This invention relates to closures for glass fruit jars or the like and has for its principal object the provision of an improved closure and means for clamping the same upon the jar in such manner as to prevent any possibility of leakage of air and consequent spoiling of the contents.

An important object of the invention is to provide a closure and clamping means therefore embodying movably mounted cam elements separately operable though intended for simultaneous operation, these cam elements being rotatable upon trunnions projecting from and formed integrally with the jar or other receptacle, it being consequently unnecessary to provide any wire supports or the like such as form parts of certain types of clamping mechanism.

Another object of the invention is to provide a closure and clamping means therefore embodying separate rotatable cam members having a U-shaped bail member connected therewith and extending transversely of the closure for urging the same into closed position and into compressing engagement with a rubber ring or gasket, the U-shaped member being so arranged and mounted that the arms thereof will lie close to the jar and the closure, distortion and stretching of the U-shaped member under strain being consequently prevented so that the proper holding action at all times will be assured.

Another object of the invention is to provide a clamping means for this purpose which is so constructed that it may be quickly engaged with or disengaged from the jar, this feature greatly facilitating initial assembling of the parts or replacement thereof in case of necessity.

Still another object is the provision of a clamping means of this character in which the cam members for placing the clamp under tension are provided with stops which coact with the arms of the closure engaging member instead of reliance being placed upon an operating bail such as is provided in some types of clamps.

A further object is to provide an improved joint between the jar and its closure so as to insure proper compression of the rubber ring or gasket and effect a positive seal.

An additional object is the provision of a closure and clamping means which will be simple and inexpensive to manufacture, easy

to operate, positive in action, efficient and durable in service, and a general improvement in the art.

With the above in view, the invention preferably consists in the arrangement and combination of parts and detailed structural features to be hereinafter more fully described and claimed, and illustrated in the accompanying drawing in which:

Figure 1 is a perspective view of a fragment of a jar or other receptacle showing the closure in place and held by the clamping means.

Figure 2 is a longitudinal section, and

Figure 3 is a detail perspective view of one of the cam members.

Referring more particularly to the drawings, the numeral 10 designates, generally, a fruit jar or the like which may be of the ordinary type and which has a mouth 11 adapted to be closed by a cap 12 disposed thereon and having a depending flange 13 telescoping within the mouth of the jar. An outstanding, annular flange 14 is formed around the mouth of the jar to provide a shoulder which constitutes a relatively broad seat for the cap and is preferably provided with an upstanding ridge or rib 15 upon which is engaged the usual rubber ring or gasket 16. That portion of the cap engaging upon the ring 16 is provided with an annular groove 12^a slightly wider than the rib 15 and, when pressure is applied to the cap for holding it in closed position, the ring 16 will be highly compressed between the ridge 15 and the groove 12^a in the cap so as to form an effective seal. The cap is preferably concavo-convex in cross section and its top is preferably provided with spaced, rounded lugs 12^b located at the center thereof for engaging a clamping device to be described.

Formed upon the jar and projecting outwardly therefrom at diametrically opposite points and in slightly spaced relation beneath the flange 14 are trunnions 17 which are substantially round in cross section and upon which are rotatably engaged cam members designated generally by the numeral 18. Each of these members may be conveniently formed from a single piece of sheet metal stamped in the proper shape and each includes a body or handle 19 of elongated form having an opening 20 therein surrounded by a flange constituting a bearing sleeve 21

for rotatable engagement upon a trunnion. The closure clamping means further includes an inverted U-shaped bail member 22 preferably of wire of suitable gauge having its bight portion 23 adapted to engage upon the cap 12 in transverse relation thereto and between the aforesaid lugs 12^b, the member further including spaced parallel arms 24 which are located immediately adjacent the ends of the trunnions 17 and which have inwardly directed bent ends 25 rotatably engaged through holes 26 in the members 18, these holes being located in spaced relation to the openings 20 or flanges 21. To facilitate movement of the members 18 without discomfort to the operator, the body or handle portions 19 thereof are preferably formed with lateral extensions 27 provided with flat bearing surfaces against which the fingers or thumbs of the operator may be engaged.

The members 18 are rotatable for the purpose of drawing down the U-shaped member or bail 22 into clamping engagement with the cap 12 and, to maintain the parts in this position, the members 18 are preferably provided with laterally extending lugs 28 so located with respect to the holes 26, where the U-shaped member is pivoted, that when the members 18 are turned to draw the U-shaped member 22 into clamping engagement with the cap, the lugs 28 will engage against the arms 24 and consequently prevent further movement in that direction as well as movement in the other direction owing to the fact that these lugs are past center with respect to the pivot points of the U-shaped clamping member.

In the operation, it is of course apparent that when it is desired to apply the cap or closure the members 18 must be in such position that the U-shaped member or bail 22 will not be under tension and may be swung downwardly out of obstructing relation to the jar mouth so that the cap may be placed in position. The cap having been seated upon the ring or gasket, with the lugs 12^b properly located to receive the bight portion 23 of the bail, the U-shaped member or clamping bail 22 is swung over to extend across the center thereof, when said portion 23 may be sprung into position between the lugs, and the members 18 are swung in a direction to draw the member 22 downwardly. This action occurs for the reason that the pivotal connections of the arms of the U-shaped member, with the members 18, are eccentric with respect to the axis of rotation thereof and it is for this reason that the members 18 have been designated as cam members, inasmuch as their movement produces a cam effect. When the members have been swung or turned to draw the clamp 22 and cap 12 toward the jar and after the members 18 have been turned to

that extent that the arms 24 are slightly beyond the axis of the members 25, or past center, the lugs 28 engage the arms and maintain the parts against movement, with the gasket 16 tightly clamped between the 70 rib 15 of the jar and the groove 12^a of the cap.

In view of the fact that the members 18 are of such simple construction and simply slipped onto the trunnions 17, it is clear that 75 the work of initially assembling the parts or replacing them in case of necessity will be greatly facilitated. However, the member 22 has sufficient rigidity to prevent accidental disengagement of the members 18 from the 80 trunnions. Attention is directed to the fact that the arms 24 are immediately adjacent the ends of the trunnions and in fact just clear the same, this being an advantage inasmuch as the bringing of the arms inwardly 85 toward the jar to the maximum extent produces likelihood of distortion or stretching of the parts under strain. It is believed that the construction, operation and advantages will be readily apparent to one skilled in the 90 art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:—

1. In combination, a container having a mouth, a closure for the mouth, trunnions formed on the container at opposite sides thereof, clamping means for the closure comprising a pair of members having bearing sleeves thereon rotatably engaged upon the trunnions and removable therefrom, and a clamping bail engageable with the closure and having its end portions pivotally connected with said members eccentric to the 105 openings therein.

2. In combination, a container having a mouth, a closure therefor, trunnions formed on the container at opposite sides thereof, clamping means for the closure comprising a pair of separate members having bearing sleeves rotatably engaged upon the trunnions and removable therefrom, a clamping bail engageable with the closure and having its end portions pivotally connected with said members eccentrically of the axes of the 115 trunnions, and stop means on said members engageable with said bail.

3. In combination, a container having a mouth, a closure therefor, trunnions formed integrally with and projecting from the container at opposite sides thereof, separate elongated members having bearing sleeves thereon rotatably engaged upon the respective trunnions and removable therefrom, said 125

members being formed with finger pieces, a clamping bail engageable transversely of the closure and having its ends pivotally connected with said members eccentrically of the openings therein, and lugs on said members engageable with the adjacent portions of said bail for effecting locking, the end

portions of said bail being past center with respect to the trunnions when in locked position.

10

In testimony, that I claim the foregoing as my own, I have hereto affixed my signature.

EDWARD P. RICE.
